ADJUSTABLE DIE FOR MAKING TRANSFORMER CORE LAMINATIONS

Frederick Leroy Patterson, Sharon, Pa.

Application June 3, 1947, Serial No. 752,195

1 Claim. (Cl. 164—31)

1

This invention relates to improved methods for making transformer core laminations and more particularly to improved practical and economical methods for cutting the component lamination pieces from strip stock of the electrical steel in a rapid, expeditious manner.

It has long been recognized that the reluctance of a laminated magnetic circuit is less when the grain structure of the steel runs in the direction of travel of the magnetic flux and it is, of course, well recognized that in the process of rolling the steel the grain structure of the steel is quite definitely aligned with the direction of rolling. Consequently in the production of magnetic circuits for electrical apparatus as in the making of transformer cores, for example, it is now usual practice to so orient the steel laminations that the original direction of rolling of the steel in the pieces is made generally coincident with the direction of flow of the magnetic flux in the assembled core. This requirement as well as the additional requirement of separability for insertion of coils presents a quite complex manufacturing problem, particularly in more advanced equipment, necessitating the production and use of a large number of separate and differently shaped lamination pieces in producing and assembling the core. The primary object of the present invention is the provision of improved methods for cutting these lamination pieces from continuous strip stock thereof whereby all the advantages of grain-flux direction coincidence may be retained while the apparatus required for cutting the lamination pieces is relatively simple and inexpensive.

The above and other objects and advantages of the invention will become apparent upon consideration of the following detailed specification and the accompanying drawing wherein there is disclosed certain preferred embodiments of the invention.

In the drawing:

Figure 1 is an assembled view of a laminated transformer core of conventional design, the individual pieces of which may be most advantageously produced by the improved methods of my invention;

Figure 2 is a detailed showing, in perspective, of one of the joints utilized in the assembly of Figure 1;

Figure 3 is a perspective view of a simpler form of laminated transformer core, the individual pieces of which may be advantageously produced by my improved methods;

Figures 4, 5 and 6 are plan views of various

2

of the individual pieces making up the core of Figure 1;

Figure 7 is a plan view of one of the individual pieces making up the core of Figure 3;

Figures 8 and 9 are schematic plan representations of my improved production methods for making the pieces of Figures 6 and 7, respectively;

Figures 10 and 11 are horizontal and vertical sections, respectively, through a die set utilized in the assembly of Figure 8;

Figures 12 and 13 are horizontal and vertical sections, respectively, through a die set used in the assembly of Figure 9; and

Figure 14 is a fragmentary horizontal section through a modified form of die set for producing the piece of Figure 6.

Referring to the drawing in detail, the core member of Figure 1 is, in accordance with usual practice, built up of a series of laminations, each lamination being comprised of a pair of end members 10 and 11, a pair of diagonally opposed side members 12 and 13, a second pair of diagonally opposed side members 14 and 15, and a yoke piece 16. Pieces 10 and 11 are identical

with each other in each lamination and in successive or contiguous laminations while the pieces 12 and 13 are identical in each lamination but are slightly modified in successive or contiguous laminations in the manner and for the purpose

30 to be hereinafter described. The latter is also true as regards the pieces 14 and 15 but the yoke pieces 16 are all identical, it being possible to obtain the required offset end portions simply by flopping the pieces over alternately all as

suggested in Figure 2. As is well understood, in the art the purpose of the offset end portions is to obtain overlapping of corresponding pieces in successive or adjacent laminations to arrive at an assembled core which is rigid structurally

40 and efficient magnetically by reason of the interlocking arrangement and the abutment of the ends of the pieces with the adjacent pieces in each lamination. The general arrangement, however, readily permits of the partial assembly

45 of the core for reception of the coil or coils after which the core may be completed by proper insertion of the bridging pieces whereupon the core is rigidly riveted together as is well understood in the art. In the core structures illustrated in Figure 1, for example, the coils employed may be encircled about the yoke built up of a multiplicity of the pieces 16.

An examination of the structure of Figure 1 and of the yoke piece 16 shown in Figure 6 shows that each yoke piece consists of a short strip having

spaced parallel side edges and a pair of right-angularly related end edges at each end of the strip. It will be observed, further, that one end point of the piece is located on one side of the longitudinal axis of the piece while the other end point is equidistantly on the other side of the axis. This means that if any such piece is flopped over side-for-side or end-for-end the end points will simply be transferred to the opposite sides of the longitudinal axis but will not shift axially along the direction of this axis. The longitudinal axis of the piece is shown at 17 in Figure 6 while the axes of the points are shown at 18 and 19. My improved method of producing the pieces 16 from strip stock and in substantially a continuous manner will now be described.

Referring to Figures 8, 10 and 11 a press is shown schematically at 20 as having a bolster 21. Associated with the press, either directly on the bolster or on tables suitably associated therewith are side guides 22 to guide strip stock 23 through the press and it should be understood that in actual practice the guides are adjustable laterally to accommodate different widths of strip whereby different widths of yoke pieces 16 may be manufactured. Secured to the bolster and ram of the press is a die set having a female die assembly mounted on the plate 24 which is preferably secured to the bolster of the press, a male die assembly 25 which is preferably secured to the ram of the press, and guide pins 26. Reference numeral 27 designates the male die in its entirety and as clearly shown in Figure 10 the forward edge of this die is formed with two linear and right-angularly disposed cutting edges 28 and 29 to collectively cut the trailing end of each piece 16 while the rear end of the die has similarly arranged but oppositely disposed cutting edges 30 and 31 to cut the forward end of each piece 16. The edges 28 and 30 are spaced slightly in a direction normal to their faces to allow the four straight edges representing the two rear end edges of a piece and the two forward edges of the next succeeding piece to be simultaneously cut in one operation as will be understood. A measuring stop 32 is positioned between the side guides 22 a predetermined interval beyond the die set and, of course, the female die will be constructed complementary to the male die. If now the leading end of a stock strip is fed to the press and a cropping stroke is first made the new end of the strip may be moved forwardly into abutting relation with the stop 32 whereby the next succeeding stroke of the press will simultaneously cut off from the strip one of the pieces 16, properly formed, and will simultaneously prepare (cut) the leading end of the next succeeding piece to be produced. In this manner I am able to produce one completed yoke piece with each stroke of the press and through the aid of automatic feed and press operation devices which are well known in this art I am able to produce these odd shaped yoke pieces at high speed and at low cost.

The general principles of my invention explained above are equally applicable for producing substantially any shape of piece which may be required in the production of laminated magnetic circuits. Thus in Figures 9, 12 and 13 I have shown an arrangement whereby the relatively simple pieces 33 used in making up the core of Figure 3 may be manufactured at a high rate of production and with an absolute minimum of material waste. I again employ a press—shown schematically at 34 and having a bolster 35—in

which is mounted a die set having a male die designated in its entirety by the reference numeral 36 and having a plan shown by the shaded area of Figure 12. It will be obvious, this die set operates upon each stroke of the press to make a 90° notch in the side edge portion of the strip and to simultaneously shear the strip transversely at a point coincident with the apex of the notch. Since only one corner of the piece 33 is eased or cut this one stroke suffices for the notching of two separate pieces and therefore to complete the production of two pieces with each stroke of the press I may provide a separate shear 37 which operates synchronously with the principal press to make a simple transverse shearing cut 38 at the trailing end of the second piece in the press. Of course, in many applications the dies for making the cut 38 may be mounted on the same set or holder which carries the die 36 so that the same press or machine is utilized for both operations. In operating the setup of Figure 9 the first cropping cut will be made by the shear 37 after which the stock is moved into engagement with the stop 39 and both the press and shear operated to simultaneously produce two of the pieces 33. In this setup, as well as in the assembly of Figure 8, compressed air, mechanical means, or other suitable expedient of which there are many in the stamping art may be utilized to remove the completed pieces upon opening of the press preparatory to the next cycle of operation.

Pieces like parts 10 and 13 of Figures 1 and 4 may be readily produced by the method of Figure 9 without use, of course, of the shear 37. Similarly the pieces 14 may be produced by the method of Figure 8, it being observed that the shape of the male die required will be identical with the shape of the space between the lefthand full line of Figure 5 and the adjacent right-angularly disposed broken lines.

In constructing the transformer core of Figure 1 it is necessary to shift longitudinally certain of the corresponding pieces in the successive laminations to secure the desired overlapping and interlocking of all the separate pieces of the core. Now to retain the rectangular solid outline or periphery of the core it will be obvious that a corner of certain of the pieces must be clipped in alternate laminations and by way of illustration the corner to be clipped off the pieces 12 and 13 in alternate laminations is indicated at 40 in Figure 4, while the corner to be clipped off the pieces 14 and 15 in alternate laminations is indicated at 41 in Figure 5. For the production of the modified pieces 14 and 15 a separate suitably modified die may be employed while the clipping off of the corner 40 of certain of the pieces 12 and 13 may more advantageously be accomplished by separate operation.

For varying sizes of core structures it may be desirable to have different extents of overlaps between the corresponding pieces of adjacent laminations. For example, in power transformers of smaller size an overlap of $\frac{1}{2}$ " may be desirable while in larger sizes an overlap of 1" may be required. As regards the outer peripheral members of the core with the exception of pieces 14 and 15 this variation may be accomplished while yet using substantially standardized pieces simply by increasing the lengths of the corners 40 and 41 which are cut off standard pieces. As regards the yoke piece 16, and the pieces 14 and 15 an increase in overlap necessitates the greater offset of the points on the ends of the pieces, and

in Figure 14 I have illustrated a composite die which may be readily changed to change the extent of offset of the points at the ends of the pieces 16. This die which is a modification of the die shown in Figures 10 and 11 includes mounting plates 42 and 42' for the female portions of the die, these plates having right-angularly disposed mounting faces 43 and 44. Since the die set is symmetrical only one symmetrical half will be specifically included in this description. Rigidly secured to the face 43 is a blade 45 the outer edge of which constitutes one of the principal shearing surfaces of the die. If the die is to be set up for cutting pieces with maximum offset for maximum overlap (1" for example) a wide blade 46 is rigidly secured to the face 44 of the carrier 42 and, as shown, the blade 46 is notched to receive a protruding end of the blade 45. The male die which is represented by the shaded area of Figure 14 comprises a permanent section 47 represented by the vertical shading or hatching lines and a detachable blade 48 which is rigidly mounted on a mounting face 49 by means of the cap screws 50. The vertical interstice between the blades 46 and 48 represents a line of shear and as there is such an assembly on either side of the die the extent of offset of the corresponding two lines of shear will be lower when the blade 48 is narrow and the blade 46 wide as will be readily understood. The setup illustrated is for larger offset and greater overlap. If less offset and less overlap is desired the blade 46 may be readily replaced with a narrower blade and the blade 48 replaced with a wider blade to bring the lines of shear inwardly to the dotted line 51. In this manner the production equipment may be made to produce pieces of widely varying dimension while the apparatus required is kept to a minimum. It should be readily apparent that the scheme of Figure 14 may be employed with equal facility to change the offset of the point on the pointed ends of pieces 14 and 15 if this is required in the construction of the particular core being considered.

In the event that it is desirable to eliminate all possible wastage of material, even at the expense of slightly more complicated die structure, it is possible to eliminate the narrow waste area which occurs between the successive punched pieces 16 of Figure 8. This is accomplished by constructing the male portion of the die of Figure 10 in a manner similar to the notch-cutting portion of the die of Figure 12. It will be understood that in this case the triangular areas of Figure 10 which are included respectively within the edges 29-30 and 28-31 will be constructed having male and female halves as does the die of Figure 12. Obviously any of the dies of my invention may be constructed in this improved manner without departing from the spirit thereof.

It should now be apparent that I have provided improved methods for producing composite pieces of electrical laminations which accomplish the objects initially set out. Through the use of relatively simple and readily procurable tools the invention provides for the production of electrical lamination pieces in a most expeditious and economical manner and, further, provides for the production of the same in a substantially continuous and automatic manner while yet maintaining the desired coincidence of the direction of grain in the steel with the direction of magnetic flux flow in the completed core to be assembled out of the individual pieces.

The above specifically described embodiments of the invention should be considered as illustrative only as obviously many changes may be made therein without departing from the spirit or scope of the invention. Reference should therefore be had to the appended claims in determining the scope of the invention.

What I claim is:

- 10 In a shear press for producing a plurality of identical elongated lamination members for a magnetic core from a length of elongated strip of transformer steel wherein the direction of flux flow is to be longitudinally along said member and with the grain structure of the member, said 15 press being adapted to receive said length of lamination steel strip to form lamination member having similarly shaped pointed ends spaced inwardly from the edges of the strip, with the apices of said points being disposed on opposite 20 sides of the longitudinal center line of the member, a die member for simultaneously forming the laterally and longitudinally offset ends of adjacent members comprising adjustable side guides for slidably engaging the edges of the steel 25 strips, a pair of longitudinally disposed V-shaped female shear die parts, the apices of said female die parts being on opposite sides of the longitudinal center line of the path of travel of the strip to be sheared, a pair of shear blades fixed on 30 the adjacent parallel faces of said female die parts, the adjacent ends of said blades being in spaced parallel, side by side relation, a second pair of shear blades mounted transversely to said first mentioned shear blades, said blades forming 35 V-shaped cutting dies with their apices in offset, spaced, side by side relation, a pair of laterally spaced longitudinally offset V-shaped male die parts, a single offset shear blade secured on one 40 pair of parallel faces of said male die parts, said offset shear blade including a narrow central portion snugly fitting between the spaced parallel ends of the first mentioned shear blades secured on said female parts, the opposed surfaces of said narrow central part being a continuous 45 part of the cutting edges of said offset shear blade, the offset portion of said offset shear blade being a continuation of the transverse surface of the V-shaped male die, a pair of shear blades secured on said other pair of male die surfaces, 50 said last mentioned shear blades engaging in shearing relation with the transverse shear blades of the female die parts, said first and last mentioned transverse shear blades being of different thickness whereby said male and female blades may be interchanged to vary the offset 55 of the apices of the die parts.

FREDERICK LEROY PATTERSON.
